METHOD FOR PRODUCING DESIGNS ON
BUILDING WALLSJohn Herck, Jacksonville, Fla., assignor to The
Ce-Brick Corporation, New Rochelle, N. Y.

Application February 12, 1949, Serial No. 76,031

3 Claims. (Cl. 18—61)

1

This invention relates to building constructions and has for its main object to provide a novel method and means to fabricate brick, stone or other designs on a wall, column, post, and the like, in a more efficient, unique, original, and highly economical manner than has been proposed heretofore.

Another object of my invention is to provide a process or method, and means for the same, as indicated hereinbefore, which enables the user to apply it for various spaces, sizes and forms, and on various objects, like walls, columns, etc.

Still a further object of my invention is to provide a method and means for producing brick, stone, or other effects on buildings with a fraction of the cost of an actual brick or stone construction.

A further object of my invention is to provide such a brick, stone and the like effect on a building wall, which at the same time will insulate the building against the cold of winter or the heat of the summer, and also fireproofing, waterproofing, termite proofing and weatherproofing a frame.

Still other objects of this invention will be apparent as the specification of the same proceeds or will be pointed out therein.

In the drawings forming a part of this specification and accompanying the same:

Fig. 1 is a fragmentary sectional view of a wooden wall to which my invention has been applied before removal of the pattern;

Fig. 2 is a perspective view of a roll of a brick pattern or patterns in sheets used in my invention;

Fig. 3 is a sectional view, the section being taken on the line 3—3 of Fig. 2;

Fig. 4 is a view of a portion of a wall finished with my brick design;

Fig. 5 shows a tool which may be used for providing brick imitation grooves, and

Fig. 6 another fragmentary view showing brick finish with said imitation score lines in it.

Referring now to the drawing in more detail by characters of reference, the numeral 10 indicates the wooden wall of a building and the like.

In practicing my invention I first apply on said wooden wall as foundation, a layer 11 of felt paper. Then I apply a layer 12 of wire mesh which may be supported by nails 20 across the face of the paper, and upon the wire mesh I now apply a coat of cement 13. While said coat is almost dry I apply by staples or special paste fluids thereon a layer of my brick pattern as

indicated at 14. This pattern I preferably make of cardboard impregnated with oil or wax and is porous to retain wetness, and preferably being of a thickness of $\frac{1}{8}$ or $\frac{1}{4}$ inch thick or to suit the thickness of brick height desired.

As clearly shown in Figs. 2 and 3 the pattern of the brick is cut out of the cardboard as indicated at 15 leaving the intact, horizontal and vertical bars 16 and 17, respectively.

My pattern 14 is preferably prepared in a long rolled up form or in special size cuts and in units of about three feet wide and three to thirty feet long rolls, and is later cut up to suit in appropriate pieces, to cover and fit any wall space or other spaces. Pattern designs of single and half bricks are also supplied for around windows and for commercial ornamentation.

The first coat of cement 13 will be allowed to dry for about six hours and pattern 14 will then be adhered by staples or by attaching by pasting fluids to it. The pattern is then dampened by a spray of water after which I apply a final layer 18 of a mixture of powdered brick cement, small granules of granite to create concrete brick form material of a desired coloring, this in a wet mixed condition, over the entire surface of the first cement covering as well as on the pattern. This last surface coating is permitted to dry about twelve hours. The aforesaid last brick-form material is pressed well over the first surface and pattern for better brick forming performance.

The last brick-form coat having been permitted to dry for about twelve hours is now thoroughly water-sprayed and water soaked for about fifteen minutes. This water spray will enter the pores of the cement and thoroughly soak the pattern paper causing it to swell and expand. The last coat material on the brick pattern effects is completely dried in the meantime, however, the material on the pattern paper has not dried except only in a small measure since cement will not adhere or dry on a wet cardboard material, oil or waxed surface. The surface over the pattern is therefore soft, powdery and undried. The brick-pattern material over the cement has completely dried thus forming a brick design form. The additional last sprinkling and wetting of the entire finished surface only tends to harden the brick effect further as the brick contracts, loosening itself from the softer material covering the pattern paper. The sprinkling of the wall on the last coat material causing the pattern paper to expand and immediately thereafter the pattern is easily removed, leaving a clean cut brick design with all

2

3

the corners perfect and showing where the pattern is removed in clear and perfect lines of the color of the original cement coat.

In a similar manner, stone or other designs may be produced by appropriate patterns. Similarly, shingles or other effects may be produced on a wall or even a roof. Also my method may be applied on rectangular, polygonal, or round posts, columns or corners as well as many different ornamental effects may be produced by my method and process.

If the wall is made of cement blocks or stucco the felt and wire mesh layers 11 and 12 may be omitted and the cement layer 13 directly applied on the wall. For marble effects, I may use a combination including marble powder and heavy coat paint covers for similar and other effects. A wire brush with widely spaced bristles 21 may be drawn across the still soft last coat application to produce score lines 22, see Fig. 6.

One highly satisfactory frame, wood walled house was finished by covering the walls with a black fifteen pound felt paper held by nails 23 holding usual thin metal discs 24 outside the felt and driven into the wood. Then a wire mesh lath was applied and held in place by headed nails driven into the wood. This was covered by a suitable cement stucco mortar troweled on and allowed to dry about six hours. On this was applied the pattern to show brick joints consisting of a skeleton of paper board used and previously described, $\frac{3}{2}$ of an inch thick, and was mounted with staples in the design desired. Following this, the wall and especially the pattern was moderately wetted. Upon this skeleton mounted pattern surface and including all the surface was troweled a wet paste of ground brick and granite particles and cement and coloring to cover the entire wall. After this final coating had hardened about twelve hours, the entire wall was wetted thoroughly for about fifteen minutes and directly thereafter the pattern was removed with ease leaving perfect brick patterns and showing clearly the mortar lines between the brick of the opposite color of the first cement coat. The effect was that of a finely finished cleaned brick house wall.

It will be understood that the basic novelty of my process lies in applying on an appropriate wall surface removable patterns having apertures of predetermined design therein, while the other portions of said patterns will indicate mortar lines in the face of the wall prepared and finished according to my invention, said lines corresponding to said predetermined design.

The spaces will be filled by an appropriate plastic material, like a mixture imitating the appearance of brick, and the exposed surface of said facing will be evened and if necessary gone over with devices to make it resemble brick or of other desired effects, after which the patterns will be removed and the desired brick or other design will be shown by grooves of mortar lines.

As has been mentioned hereinbefore, in this

4

manner large surfaces of a wall may be ornamented and made to appear as brick or other stone wall with mortar lines in an efficient, easy, inexpensive and quick manner as against the slow laborious, expensive methods heretofore proposed for such ornamentations of walls.

In the preferred practice of my invention I prepare specific foundations for said pattern and the ornamental face layer to be formed through the use of said pattern in the manner indicated, and said face layer is evened over the pattern, said pattern then being removed after the operations described.

As has been specifically described I prefer to have the pattern made of cardboard material adapted to be soaked with water and to be easily removed in such condition.

Having thus described certain embodiments of the invention in some detail, what is claimed is:

1. A process for preparing an ornamental face on a wall including mortar lines, consisting in applying a removable pattern having bars therein corresponding to the mortar line design to be produced on the wall, filling the spaces between the mortar line bars with an appropriate plastic material, permitting said plastic material to harden and then removing said pattern whereby mortar lines of predetermined depth will be produced between the filled in portions of the pattern, said pattern being of water absorbing character, and being easily removed when soaked with water, and applying water on the ready face on the wall for easier removing of the pattern.

2. In a process for producing an ornamental face on a wall, the steps of securing a removable pattern on the wall, said pattern having apertures therein corresponding to the design to be produced, filling said apertures with a plastic composition, permitting said composition to harden, wetting the pattern, said pattern being adapted to absorb water and to be soft, easily tearable and removable in such condition.

3. The process, method and system of preparing an ornamental face on a wall which includes applying a coat of cement, applying to the still soft cement an oiled paper pattern of crossed resisting lines in the pattern of dividing lines of brick, applying a colored cement coat to the cement over the pattern so that the drying cement coat growing harder will separate itself through contraction from the pattern and the pattern will absorb the moisture from the drying cement coat, and applying water spray on the pattern for an easy removal.

JOHN HERCK.
